SOOT AND CREOSOTE ELIMINATOR

Paul J. Libby, Lewiston, Maine

Application November 13, 1934, Serial No. 752,869

1 Claim. (Cl. 126—312)

This invention relates to furnace constructions and more particularly to a means adapted to be inserted in a chimney to eliminate the accumulation of soot and creosote.

5 An object of this invention is to provide an eliminating means of the character set forth which can be readily mounted in the present chimney constructions so that a constant draft will be maintained through the chimney without 10 impairing the draft in the furnace or stove.

Another object of this invention is to provide a device of this kind which will not only eliminate the accumulation of soot and creosote but will also prevent the pocketing or accumulation of un- 15 burned gases in the chimney which thereby cause backfiring or explosions in the chimney.

A further object of this invention is to provide a device of this kind which will operate to constantly withdraw air out of the furnace room or cellar so that the air in the cellar will be kept 20 clean by reason of the removal of the gas filled air through the chimney.

The above and various other objects and advantages of this invention will in part be described 25 and in part be understood from the following detailed description of the present preferred embodiment, the same being illustrated in the accompanying drawing wherein:

Figure 1 is a vertical section of a flue or 30 chimney having a furnace connected thereto and having a device constructed according to the preferred embodiment of this invention.

Figure 2 is a perspective view partly cut away and in section of the draft controlling means.

Figure 3 is a vertical section taken substantially 35 through the center of the device.

Referring to the drawing wherein like numerals of reference designate corresponding parts throughout the views, the numeral 10 designates generally a casing comprising a cylindrical body 40 11 provided with a flanged inner end 12 having a plurality of openings or ports 13 therethrough. The outer end of the casing 10 is closed by means of a plate 14 provided with a plurality of openings 15 and this plate 14 is extended beyond the periphery of the casing 11 so as to provide a marginal flange 16.

An inner baffle member, generally designated as 17, is disposed in spaced relation to the inner end 12 and this baffle member 17 comprises a relatively rigid metal plate 18 having a plate or disk 19 contacting with the outer face thereof and which disk 19 is preferably constructed of asbestos or other fire-proof material.

55 A second or outer baffle 20 is disposed in out-

wardly spaced relation to the inner baffle 17 and comprises a disk or plate 21 preferably of metal and a disk or plate 22 preferably of asbestos which contacts with the outer face of the metal plate 21. The two baffles 17 and 20 have their outer marginal portions disposed in spaced relation to the inner surface of the casing 11 so that air may freely pass thereabout. The two baffles 17 and 20 are held in spaced relation to each other by means of a substantially U-shaped spacing member 23, 10 and a second U-shaped spacing member 24 engages the outer baffle 20 and holds this baffle 20 in spaced relation to the outer wall 14.

A bolt 25 extends concentrically through the casing 11 and through the baffles 17 and 20 together with the spacing members 23 and 24 and preferably the head 26 of the bolt 25 engages on the outside of the outer wall 14, and a nut 27 is threaded onto the bolt 25 and disposed inwardly of the inner wall 12 and holds the baffles 17 and 20 in assembled relation. A wing nut 28 is threaded onto the inner end of the bolt 25 and a washer 29 is interposed between the wing nut 28 and the inner end member 12.

In the use of this device, the hollow body or 25 casing 10, as will be noted from the drawing, is inserted in a chimney C at a point below the entrance of the smoke pipe P in the chimney. In chimney constructions, it is common for the soot and creosote to accumulate in the lower portion or chamber below the entrance of the smoke pipe P into the chimney in view of the fact that no air enters the lower portion of the chimney. When the furnace is in full draft, the soot or creosote will not ordinarily accumulate in the chimney C due to the substantially perfect combustion, but where the drafts of the furnace are shut down and the furnace checked, there is an imperfect combustion in the furnace and in the pipe P, and the unburned gases then pass into the chimney C where there is formed a down draft which, upon striking the unburned gases, causes condensation and precipitation. This precipitation accumulates in the chimney C and after a period of time, the creosote accumulated 30 in the chimney will seep through the bricks and not only cause damage to the walls and paper on the walls, but this accumulation of creosote upon 35 restarting of the furnace has a tendency to catch fire. However, through the use of the structure hereinbefore described, the dry air normally in 40 the cellar will enter the intake ports 15 and pass about the baffles 20 and 17, respectively, and then enter the chimney C through the outlet ports 13. The use of the baffles 17 and 20 will have a 45

50 55

tendency to retard the flow of air so that while a quantity of air is permitted to enter the lower portion of the chimney, this quantity of air will not be sufficient to cut down the suction through the furnace but will in effect act to improve the suction through the furnace. It will be apparent from the foregoing that with the use of this device, a draft of dry air will be formed in the chimney at all times irrespective of whether the furnace connected to the smoke pipe P is open or shut down.

The device hereinbefore described is preferably positioned within the chimney or flue C at a point closely adjacent the point where the smoke pipe P discharges into the chimney. It is for this reason that there are provided a pair of baffles disposed in spaced relation to each other and to the inner and outer walls of the device so that the innermost baffle will receive the greatest quantity of heat and the outer baffle will be engaged by the incoming air which will maintain it in a cool state. Furthermore, by using two baffles a constant stream of cool air is permitted to pass through the device and due to the position of the device, with respect to the smoke

pipe, a draft of cool air will strike the hot gases or heated air discharged into the chimney by the smoke pipe. In this manner no hot air or gases will be permitted to flow down into the space below the smoke pipe P and thus no trap will be formed within the chimney.

What is claimed is:—

A soot eliminator as set forth, comprising a cylindrical casing adapted to be inserted in a chimney opening, a perforated cap on one end 10 of the casing, a perforate plate on the other end of the casing, a pair of spaced apart baffles disposed within the casing and having a diameter less than the diameter of the casing whereby to permit air to pass about the marginal edges 15 thereof, a bolt extending axially of the casing through the cap and the plate for supporting the baffles within the casing and holding the parts in assembled relation, a pair of U-shaped spacing members carried by the bolt for holding the baffles in spaced apart relation and a fibrous fire-proof member engaging against a face of each plate.
